UNITED STATES PATENT OFFICE.

JOHN L. HAMILTON, OF CHICAGO, ILLINOIS.

DESIGN FOR A LAMP-POST.

41,069.

Specification for Design.

Patented Jan. 3, 1911.

Application filed November 11, 1910. Serial No. 591,889. Term of patent 14 years.

To all whom it may concern:

Be it known that I, JOHN L. HAMILTON, a citizen of the United States, residing at Chicago, in the county of Cook and State of Illinois, have invented a new, original, and ornamental Design for a Lamp-Post, of which the following is a specification, reference being had to the accompanying drawing, forming part thereof.

The figure is an elevation of a lamp-post, showing my new design.

I claim:

The ornamental design for a lamp-post, as shown.

JOHN L. HAMILTON.
